UNITED STATES PATENT OFFICE.

MARK H. MARTIN, OF BALTIMORE, MARYLAND, ASSIGNOR TO THE SYMINGTON COMPANY, OF NEW YORK, N. Y., A CORPORATION OF MARYLAND.

CAST-STEEL SIDE FRAME.

Application filed May 5, 1925, Serial No. 28,066. Renewed August 20, 1928.

This invention relates to side frames for railway trucks and more particularly to cast frames having journal boxes integral therewith.

5 The principal object of my invention, generally considered, is the production of cast integral side frames in which the various sections of the members thereof are so designed that maximum strength is obtained 10 with minimum weight of metal and in which special reinforcements are employed at critical positions.

An object of my invention is the provision 15 of a cast side frame for railway car trucks in which the various members thereof are generally T-shaped in cross-section with the main webs of said sections extending substantially upright and in which the bottom flange of the tension member joins with the 20 integral journal boxes at approximately the upper corner of the inner brass lug and falls below the normal upper inner corner of the journal box, an additional reinforcement being provided between the lower 25 flange of the tension member and the inner side of the journal box in the form of a flanged web extending from the lower face of the lower flange of the tension member to the inner wall of the corresponding journal 30 box.

Another object of my invention is the provision of a cast side frame for railway car trucks comprising a compression member, a tension member, and bolster column guide 35 members therebetween, with a window opening formed between the bolster guide members and the compression and tension members, said tension member being formed with an intermediate substantially horizontal portion and with diagonal end portions extending therefrom, the lower flanges of the diagonal end portions connecting with the corresponding flange on the horizontal portion below the window opening 40 and inwardly of the bolster guide portions.

A further object of my invention is the provision of a cast steel side frame for railway car trucks formed with a compression member, a tension member and bolster 50 column guide or strut members spacing intermediate portions of said compression and tension members and forming therebetween a bolster or window opening, all of said members being generally T-shaped in cross-section and the tension member formed with

an intermediate substantially horizontal portion and diagonally extending end portions, the junction between the diagonal portions of the tension member and the bolster column guide members being strengthened 60 by a T-section reinforcement extending from the lower flange of the diagonal tension portions at the junction of the tension member and strut and diagonally from the window opening corners. 65

A still further object of my invention is the provision of a cast steel side frame for railway car trucks formed with a tension member, the upper flange of which is wide in the center to form a spring seat and tapered in width toward the ends thereof across the lower portions of bolster column guide members, and extended as a top flange of 70 said tension member, then around the triangular openings on opposite sides of the 75 bolster column guide members.

A still further object of my invention is the provision of a cast side frame for railway car trucks formed with a compression member having a substantially upright web 80 and top flange portion, said top flange being curved downwardly at the ends thereof and united with the roofs of integral journal boxes substantially on the line with the outer brass lugs from which it merges into the 85 outer side walls of said journal boxes.

An additional object of my invention is the provision of cast side frames for railway car trucks including brake hanger brackets substantially U-shape in cross-section, the web of the U-section being sloped upwardly and merging with the top flange of the side frame compression member and the legs of the U extending and joining with the lower flange of said compression member. 90 95

Other objects of my invention, relating to the particular construction and arrangement of the various parts, will become clearer as the description proceeds. 100

Referring to the drawings illustrating my invention, the scope whereof is pointed out in the claims:

Figure 1 is a side elevation of a cast side frame for railway car trucks embodying my invention, a portion of one end of said side frame being shown in section. 105

Figure 2 is a plan view of the side frame of Figure 1, shown partly in section and partly broken away. 110

Figure 3 is a cross-sectional view taken on the line 3—3 of Figure 1, looking in the direction of the arrows.

Figure 4 is a sectional view on the line 5 4—4 of Figure 1, looking in the direction of the arrows.

Figure 5 is a sectional view on the line 5—5 of Figure 1, looking in the direction of the arrows.

10 Figure 6 is a sectional view taken on the line 6—6 of Figure 5, and looking in the direction of the arrows.

Figure 7 is a sectional view on the line 7—7 of Figure 5, looking in the direction 15 of the arrows.

Figures 8, 9, 10 and 11 are sectional views on the correspondingly numbered lines of Figure 1, Figure 11 being taken looking in the direction of the arrows.

20 Referring to the drawings in which similar reference characters designate like parts, there is illustrated a cast side frame 1, in the embodiment shown comprising a compression member 2, a tension member 3, 25 bolster column guide members 4, and journal boxes 5. The compression, tension and bolster guide members are formed generally T or I shaped in cross-section. That is, they comprise web portions 6 disposed in substantially upright position, and flanged portions disposed on opposite edges of the web portion, said flanged portions being of different widths, and some of them tapering in width so that the members are thought more 35 properly considered as generally T-shaped in cross-section rather than I-shaped, although they have flanges on each side of a web portion.

The tension member 3 is formed with an 40 intermediate substantially horizontal portion 7 and diagonally disposed end portions 8 and 9 from said central portion 7. The diagonal portions 8 and 9 preferably connect with the journal boxes 5 at the junction between the journal box roof 10 and the corresponding inner brass lug 11. That is, the lower webs or flanges of said diagonal tension portions form continuations of the corresponding webs or flanges of the horizontal portion 7 and connect with the journal boxes 50 below the normal inner corners thereof.

For strengthening the union between the side frame proper and the journal boxes 5, reinforcing portions 12, extending from the 55 lower flanges of the diagonal tension members 8 and 9, are provided. These reinforcements preferably take the form of webs 13 in line with the webs 6 of the side frame members and flanges 14 extending therefrom, 60 said flanges and webs connecting directly with the lower flanges of the tension members and the inner side walls of the journal boxes, the flanges 14 preferably being substantially horizontal and connecting with 65 the journal boxes at approximately the point

of juncture between the lower portion of the inner brass lugs and the main walls of the journal boxes, as most clearly illustrated at the left side of Figure 1.

For rigidly connecting the outer sides of 70 the journal boxes with the side frame, the upper flange of the compression member 2 is preferably curved downwardly at its outer ends, as shown at 15, and connects at each end with the journal box roof, approximately in line with the inner face of the outer brass lug 16. From the point of junction with the corresponding roof 10, the flange is then continued, as shown at 17, as part of the sloping outer wall of the corre- 75 sponding journal box. 80

As a further bracing means between the journal boxes and side frame proper, angular web portions 18 are provided which extend from the roof of each journal box to the 85 web 6 of the side frame proper. Between the upper and lower arch bars or compression and tension members 2 and 3, respectively, and the bolster column guide or strut members 4, is formed a bolster or window 90 opening 19, and on the outer sides of the bolster column guide members 4, between the compression and tension members, are formed the triangular openings 20 and 21. The bolster or window opening 19, as is usual, is formed wider at its lower than at its upper part so that the track bolster may be readily inserted therein, the upper portion being provided with guiding flanges 22 and 23. 95

The upper web or flanges 24 of the tension member 3 between the bolster column guide portions 4, is formed relatively wide and preferably provided with the spring seating bosses 25 on the upper surface thereof so that said web forms a spring seat of ample width for the accommodation of the bolster springs. Said spring seat is preferably tapered beyond the spring seating portions 25 and continued below the bolster 100 column guide portions 4 as the upper web or flanges of the tension member 3, said upper web tapering in width from the junction with the spring seating portion 24 and extending in tapered formation for the full 105 length as the upper flanges of the tension member and preferably continuing around the triangular openings 20 and 21, so as to form the lower flanges 26 of the compression member adjacent said openings, where 110 it gradually merges to a uniform width. This feature is most clearly illustrated in Figure 2, and results in economy of construction as well as pleasing appearance. 115

The lower flanges of the diagonal members 8 and 9 connect with the lower flanges of the horizontal portion 7, beneath the bolster or window opening 19 and inwardly of the bolster column guide portions 4. Such a construction improves the strength char- 120 125 130

acteristics of the frame and it will be apparent that the lower flanges of the diagonal portion of the tension member thus extend beyond the upper flanges thereof so that the upper horizontal flanges on the tension member are longer than the corresponding lower flanges and thereby form a spring seating area of adequate proportions.

The spring seating surface 24 is preferably reinforced by webs 27, most clearly shown in Figure 3, and preferably extending from beneath the portions 25 to the junction between the inclined lower flanges on the tension member and the horizontal flange thereof.

For strengthening the critical portions of the tension member 3 beneath bolster column guide portions or struts 4, reinforcements 28 are provided. These reinforcements preferably take the form of T-shaped extensions diagonally disposed from the lower corners of the window opening 19 and formed with webs 29 extending as continuations of the web 6 of the tension member, 25 and outlined by curved flanged portions 30, merging at their ends into the lower flange of the tension member, said flanges 30 preferably not extending lower than the lowermost portion of the flange of the tension member 3. These T-shaped portions 28 are most clearly shown in section in Figure 10, from which it will be apparent that their flanges 30 are relatively narrow compared with the lower flange of the tension member.

Integral spring hanger brackets 31 are preferably provided, said brackets being generally U-shaped in cross-section and connected with the inner portion of the side frame by having the web portion of the U slope upwardly and connect with the upper flange of the compression member 2, as shown most clearly in Figure 3. The flanges of the U preferably extend in substantially vertical planes, one of said flanges connecting directly with the lower flange or bead of the compression member and the other being bent angularly toward said bead for connection therewith, as shown at 32. The reinforcing webs 33 preferably connect the beads framing the triangular openings 20 and 21 with the junctions between the lower horizontal bead or flange on the compression member and the bolster guide portions 22 and 23.

The compression member 2 is preferably of lighter section than the tension member because it is called upon to bear less stress than said tension member and the inner flanges of all of said members are preferably formed thinner than the corresponding outer flanges thereof. The reason for making these flanges of different thicknesses is that truck side frames of this type are cast 65 with the outer or front face on the cope or

upper side of the mold so that when the metal is poured into the mold the rear flange of the side frame is first formed and as the pouring is continued the metal rises until finally the front flange is formed. Unless provision is made to take care of the difference in quality between the metal forming the front and rear flanges by increasing the thickness of the front flange, it will be obvious that the rear flange will have greater strength which results, when the truck is in service, in stressing the outer flange to a greater degree in proportion to its strength than the inner flange.

By providing, as above pointed out, flanges of unequal thicknesses this defect has been obviated so that the side frame is provided with opposite flanges of uniform strength. Of course, if the side frame were cast in the opposite way, that is with the inner or back face in the cope side of the mold, the difference between the flange thicknesses would be reversed, the flanges formed in the cope side of the mold always preferably being heavier than those formed in the lower or drag side thereof.

In view of the foregoing, it will be appreciated that I have provided an improved integral side frame which is preferably formed of cast steel with journal boxes and 95 brake hanger brackets preferably, but not necessarily, integrally united therewith.

Having now described my invention, I claim:

1. A truck side frame comprising a tension member, a compression member, bolster guide columns interposed between intermediate portions of said members, said members being generally T-shape in section, with the web of said section arranged in substantially upright position, journal boxes at the ends of the frame, the lower flange of the tension member joining the journal box roof at the corner of the inner brass lug and falling below the normal upper inner corner thereof.

2. A truck side frame comprising a tension member, a compression member, bolster guide columns interposed between intermediate portions of said members, said members being generally T-shape in section with the web of the section arranged in substantially upright position, journal boxes at the ends of the frame, said frame members and journal boxes being cast as one piece, the lower flange of the tension member intersecting the journal box below the upper inner corner thereof and united with the roof thereof at substantially the junction of the inner brass lug therewith.

3. A truck side frame comprising a tension member, a compression member, bolster guide columns interposed between intermediate portions of said members, said members being generally T-shape in section with the

web of the section arranged in substantially upright position, journal boxes at the ends of the frame, the under face of the lower flange of the tension member being connected to the inner side wall of the journal box by flanged web portions, substantially T-shape in section.

4. A truck side frame comprising a tension member, a compression member, bolster guide columns interposed between intermediate portions of said members, said members being generally T-shape in section with the web of the section arranged in substantially upright position, journal boxes at the ends of the frame, said frame members and journal boxes being cast integrally as one piece, the underface of the lower flange of the tension member being integrally connected to the journal box by a flanged web portion, forming with said lower flange an approximate I-section.

5. A truck side frame comprising a tension member, a compression member, bolster guide columns interposed between intermediate portions of said members, said members being generally T-shape in section with the web of the section arranged in substantially upright position, journal boxes at the ends of the frame, said frame members and journal boxes being cast as one piece, the lower flanges of the tension member intersecting the journal box below the upper inner corner thereof and united with the roof thereof at substantially the junction of the inner brass lug therewith, the under face of the lower flange of the tension member being connected to said journal box by a gusset portion with a lower flange extending to the journal box at substantially the lower end of the inner brass lug.

40 6. A truck side frame comprising tension and compression members with bolster guide columns interposed therebetween and forming a bolster opening, said members being generally T-shape in section with the webs substantially upright, the tension member being formed with a substantially horizontal central portion under the bolster opening and diagonal end portions, the lower flange of each diagonal portion connecting with the lower flange of the horizontal portion inwardly of the bolster guide columns.

55 7. A truck side frame comprising tension and compression members with bolster guide columns interposed therebetween and forming a bolster opening, said members being generally T-shape in section with the webs substantially upright, the tension member being formed with a substantially horizontal central portion under the bolster opening and diagonal end portions, the lower flange of each diagonal portion extending beyond the upper flange thereof and connecting with the lower flange of the horizontal portion be-

low the bolster opening and inwardly of the bolster guide columns.

8. A truck side frame comprising a compression member, a tension member formed with an intermediate substantially horizontal portion and diagonal end portions, bolster guide columns interposed between said compression and tension members and forming a window opening therebetween, said tension member being generally T-shape in section with the web substantially upright, and a T-section reinforcement applied to the lower flange of the tension member at the junction of each column therewith.

9. A truck side frame comprising a compression member, a tension member formed with an intermediate substantially horizontal portion and diagonal end portions, bolster guide columns interposed between said compression and tension members and forming a window opening therebetween, said tension member being generally T-shape in section with the web substantially upright, and a T-section reinforcement applied to the lower flange of the tension member at the junction of said columns therewith, said reinforcements extending generally diagonally downward from the lower corners of the window opening.

10. A truck side frame comprising a compression member, a tension member formed with an intermediate substantially horizontal portion and diagonal end portions, bolster guide columns interposed between said compression and tension members and forming a window opening therebetween, said tension member having a relatively wide upper flange on its horizontal portion, forming a spring seat, said flange being extended as the upper flange of the diagonal end portions of the tension member and tapered in width around the triangular openings formed between compression, tension and bolster guide portions.

11. A truck side frame comprising a compression member, a tension member, journal boxes connected at the ends thereof, the compression member being formed with a top flange curved downwardly at its ends and united with the roof of each journal box in line with the wall forming the outer brass lug.

12. A truck side frame comprising a compression member, a tension member, journal boxes connected at the ends thereof, the compression member being formed with a top flange curved downwardly at its ends and united with the roof of each journal box in line with the wall forming the outer brass lug, the outer end walls of the journal boxes, on each side of the said brass lug, being sloped as continuations of the compression member top flange.

13. A truck side frame comprising a com-

- pression member generally T-shape in section with an upper flange and substantially upright web and a brake hanger bracket connected thereto, said bracket being generally U-shape in section with the web of the U sloped upwardly and directly connected to the upper flange of the compression member.
14. A truck side frame comprising a compression member generally T-shape in section with an upper flange and substantially upright web with a lower flange or bead thereon, and a brake hanger bracket connected integrally to said compression member, said bracket being generally U-shape in section with the web of the U merging into the upper flange of the compression member and the legs of the U connecting with the lower bead on the compression member.
15. A truck side frame comprising a compression member generally T-shape in section with an upper flange and substantially upright web with a lower flange or bead thereon, and a brake hanger bracket connected integrally to said compression member, said bracket being generally U-shape in section, the legs of the U connecting with the lower bead on the compression member.
16. A truck side frame comprising a compression member, a tension member and bolster column guides interposed between intermediate portions thereof, said members being generally T-shape in cross-section with flanges extending inwardly and outwardly from substantially upright web portions, the compression member being of lighter section than the tension member, the inwardly extending flanges of said members being of different strength than the corresponding outwardly extending flanges.
17. A truck side frame comprising a compression member, a tension member and bolster column guides interposed between intermediate portions thereof, said members
- being generally T-shape in cross section with flanges extending inwardly and outwardly from substantially upright web portions, the inwardly extending flanges being of different thicknesses from the outwardly extending flanges, for purposes of strength equalization.
18. A truck side frame comprising a compression member, a tension member and bolster column guides interposed between intermediate portions thereof, said members being generally T-shape in cross-section with flanges extending inwardly and outwardly from substantially upright web portions, the compression member being of lighter section than the tension member with the inwardly extending flanges of all of said members being thinner than the outwardly extending flanges, to equalize the strength thereof.
19. A truck side frame comprising a compression member, a tension member, bolster guide columns interposed between said compression and tension members and forming a window opening therebetween, those portions of the tension member adjacent the junctions with the bolster columns being reinforced by flanged webs extending diagonally downward and outward from the lower portions thereof and the lower outlines of said webs being convex downwardly.
20. A truck side frame comprising a compression member, a tension member, bolster guide columns interposed between said members and leaving a window opening therebetween, said tension member comprising a lower transversely extending portion continued from beneath the window opening toward the ends of the frame, said portion being reinforced immediately below the bolster columns by upright web portions, the ends of which gradually decrease in strength and merge into the tension member on opposite sides of the bolster columns.

In testimony whereof I affix my signature.
MARK H. MARTIN.
